Specification for Design.

Patented Nov. 28, 1911.

Application filed February 27, 1911. Serial No. 611,295. Term of patent 14 years.

To all whom it may concern:

Be it known that I, CHARLES A. BAILEY, a citizen of the United States, residing at Cromwell, in the county of Middlesex and State of Connecticut, have invented a new, original, and ornamental Design for Toy Banks, of which the following is a specification, reference being had to the accompanying drawing, forming part hereof.

In the drawing: Figure 1 is an elevation of the front of the bank. Fig. 2 is an ele-

vation of the back of the bank. Fig. 3 is an elevation of one of the sides of the bank. Fig. 4 is a plan or top view of the bank.

I claim:

The ornamental design for a toy bank, as shown.

CHARLES A. BAILEY.
